FINISHING TOOL

Filed Sept. 26, 1925

Ernest L. Linton
By his Attorney,
Nelson W. Howard

UNITED STATES PATENT OFFICE.

ERNEST ASHTON, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

FINISHING TOOL.

Application filed September 26, 1925. Serial No. 53,922.

This invention relates to finishing tools and is herein illustrated as embodied in a buffing roll of a type used extensively in the manufacture of boots and shoes, although 5 the invention is applicable to treating tools of other types and designed for performing other operations.

In rolls of this type, in which the abrasive material is usually supplied by means of a 10 cover of abrasive material such as sandpaper, which is wrapped around the roll, it has for a long time been customary to hold the abrasive cover in place upon the roll by means of a series of paper-clamping hooks 15 inserted radially into the body of the roll and arranged to be drawn down by an internally-disposed actuator tightly against one edge of the sheet of material to clamp it in place. One such construction which has 20 been used extensively and with a high degree of success is illustrated in United States Letters Patent No. 1,014,094, granted January 9, 1912, upon the application of W. A. Reed. One reason for the success of that 25 arrangement lies in the fact that it provides a device for detachably securing the hooks to an actuator bar so that broken hooks may be replaced without necessitating the disassembly of the roll as a whole.

30 For the purpose of still further facilitating removal and replacement of abrasive-cover clamping members in a roll of the type above referred to, the present invention provides an improved abrading tool comprising, 35 as herein illustrated, a series of abrasive-cover engaging and retaining hooks individually connected to a common actuator, together with a sliding locking device for pushing home the retaining hooks as they 40 are brought into engagement with the actuator bar and securing them in this relation. As a result, in the illustrated construction to be more fully described hereinafter, the operator is enabled to remove a broken hook 45 and replace it without disturbing the co-operating engagement of the other hooks and the bar within the roll, and with the assurance that the end of the hook which he has placed in the roll is correctly engaged 50 with the actuator bar. This operation will be followed by movement of the locking device to secure all the hooks in co-operating engagement with the actuator bar.

For a better understanding of the exact construction of my improved abrading tool 55 reference may be had to the following specification and claims taken in connection with the accompanying drawings in which:

Fig. 1 is a fragmentary, transverse section through an abrading tool to which my invention has been applied;

Fig. 2 is a plan view of the actuator bar and its associated locking device;

Fig. 3 is a side elevation thereof;

Fig. 4 is a fragmentary, perspective view 65 of a portion of the same, showing a cover-clamping hook locked in engagement with the actuator bar;

Fig. 5 is a similar view of the under side of the locking device at the other end;

Fig. 6 is an end view of an abrading tool employing my invention;

Figs. 7, 8 and 9 are fragmentary views of a portion of an actuator bar and associated cover-clamping hook together with a 75 modified form of the locking device.

The illustrated abrading tool includes a cylindrical, wooden core 10 (Fig. 1) surrounded by a resilient covering 12 of felt, these body parts being held in position upon 80 a power-driven shaft 14 by means of collars 16 (Fig. 6) secured to the shaft at the two ends of the roll. Provision is made for limited rotation of the body parts with respect to said collars and the shaft, all as shown 85 in the above-mentioned Letters Patent No. 1,014,094, to which reference may be had for a more complete description of the parts not fully illustrated or described herein. The abrasive cover 20 is secured in position upon 90 the roll by forcibly threading one edge portion 22 of a sheet of abrasive material over the flattened outer terminal portion 28 of a series of paper-clamping hooks 24 distributed lengthwise of the buffing roll and, after 95 wrapping the sheet of material around the roll, bringing the other edge 26 thereof into position for engagement by the overhanging ends 28 of the clamping hooks 24. These hooks 24 are provided with depending cylindrical shanks 30 which extend radially into the body of the roll and are detachably secured to an actuator bar 32 extending longitudinally of the buffing roll within a suitably formed slot 34 in the core 10. This 100 bar 32 may be moved outwardly to lift the

hooks or inwardly to bring them into the clamping position illustrated in Fig. 1. The inward and outward, substantially radial movement of the hooks 24 and the bar 32 may be effected, as in the patented device, by relative movement of the roll and its collars 16 to cause the cam slots 36 (Fig. 6) in the collars, engaging the ends of the actuator bar 32, to move said bar. Concealed 10 spring-pressed latches are provided, as in the patented construction, to prevent rotation of the body parts with respect to the collars, and a manually operated plunger 38 is slidably mounted to project through the right-hand collar to a position where it may be depressed to release these latches.

In the construction illustrated in Figs. 1 to 6, the actuator bar 32 is provided with a series of hook-shaped portions 40 whose overhanging ends forming shoulders extend transversely of said bar and form undercut recessed projections opening laterally and longitudinally of the bar. The inner lower ends of the clamping hooks 24 are provided with arms 42 extending at right angles to the shanks of said hooks and also at right angles to the direction of the overhanging, flattened ends 28 of the hooks. These inner ends 42 are normally disposed parallel to the axis 20 of the roll and are adapted to be moved longitudinally of the actuator 32 to bring said arms 42 into the recesses of the hook portions 40. To this end the felt covering 12 and the wooden body portion 10 are provided with elongated slots 44 through which the arms 42 may be inserted at a position at 25 one side of the hook portions 40 and then moved axially of the roll to insert the arms 42 into the recesses of the bar, thereby interengaging and mutually interlocking the hooks and the bar at points inside of the resilient covering. Preferably and as illustrated, one side of the slot 34 within the roll is provided with a metallic lining plate 46 which, co-operating with the open sides of 30 the hook portions 40 (see Fig. 1), prevents accidental lateral disengagement of the arms 42 from the hook portions 40 circumferentially of the roll such as might result in case 35 the slot 34 became enlarged by wear.

The paper-clamping hooks 24 are held interlocked with the lateral recessed extension of the actuator bar 32 by means of a locking device 50 in the form of a thin, metal plate disposed along one side of the actuator bar 45 within the slot 34 of the body portion 10 of the roll. This locking device 50 is provided with separated lips 52 bent laterally over the upper surface of the actuator bar at positions adjacent to the hooks thereon and each 50 provided with an upstanding flange 54 and thus constitutes a shifting abutment to hold the hooks. The lower edge of the locking device 50 is bent inwardly to form a bottom face 56 (Fig. 1) disposed beneath the actuator

bar 32 to hold the locking device 50 upon the bar. Accidental lengthwise displacement of the locking device 50 with respect to the actuator bar 32 is avoided by slitting the ends of the bottom face 56 at 58 and 60 to form tongues 62 and 64 which are bent inwardly before the locking device is applied to the bar so that they frictionally engage it. The end 66 of the tongue 64 is bent in rather sharply so that it curls over 60 a shoulder 68 in the bar 32 and even more effectually prevents displacement. It should be noted that the operation of removing and replacing hooks is always undertaken when the actuator bar is moved outwardly to lift the hooks away from the roll by rotation of the collars 16, and in this position apertures 61 (Fig. 6) in said collars come into registration with the ends of the actuator bar and allow the insertion of a suitable tool to 65 press the locking device 50 in one direction or the other as may be required.

The arrangement described provides then not only for the ready manipulation of the roll to remove and replace the abrasive coverings thereon and to hold said coverings in place by means of hooks which are pressed inwardly so that their outer ends lie beneath the level of the resilient covering of the roll but provides also an arrangement facilitating the removal and the replacement of individual paper-clamping hooks in case of breakage. To carry out this operation the operator will first depress the latch-releasing plunger 38 on the end collar 16 and then effect a relative rotation of the body of the roll and said collars, thereby lifting the actuator bar 32 and the associated clamping hooks 24 to release the abrasive cover and to bring said hooks 24 into a raised position where the upper ends of the shanks 30 of the broken hooks will project above the resilient cover of the roll. The operator will then insert a suitable tool through one of the apertures 61 in a collar 16 and move the locking device 50 longitudinally of the roll. This will move the upstanding flanges 54 on said locking device away from the clamping hooks 24 and allow movement longitudinally of the roll of any of the hooks which it is desired to remove and replace. A simple translatory movement thus parallel to the axis of the roll will move the arm 42 of any of said hooks laterally from beneath the coacting hooked portion 40 of the actuator bar, whereupon it may be lifted out of the slot 44 in the roll. In inserting another hook, the operation is reversed and after inserting the end of a hook into a slot 44 of the resilient cover of the roll, the hook will be moved longitudinally of the roll to bring its arm 42 into interlocking position beneath the shoulder formed by the hook portion 40 of the actuator bar. The previously mentioned elongation of the slots 44

not only permits passage of the arms 42, but also accommodates the shank portions 30 of the hooks 24 in their translatory movement above described. When so inserted, a hook 5 will remain in position and it will be noted that the operation just described does not necessitate the disengagement of any of the other hooks from the actuator bar. By inserting a suitable tool through the aperture 10 61 at the other end of the roll, the locking device 50 may then be moved back into the position illustrated in Figs. 4 and 5, and when so moved, it will push home all of the paper-clamping hooks and securely hold 15 them in co-operative engagement with the actuator bar. The locking device just described, by reason of being constructed of sheet metal, is comparatively rigid in spite of its relatively great length and is, further- 20 more, so confined between the actuator bar 32 and the slot 34 in the body of the roll that there is little chance that it will become bent or distorted so as to interfere with the movement of said locking device.

25 As in the construction of the Patent No. 1,014,094, deflection of the central part of the actuator bar is prevented by means of a hook 70 (Fig. 1) which is formed as an integral part of a ring 72 which is rigidly 30 connected to the collars 16. When the collars 16 and the body parts of the roll are relatively rotated to cause the elevation of the actuator bar 32 and its attached hooks, said bar is withdrawn laterally from the 35 opening 74 of said hook so that there is no interference with the movement of the bar. In accordance with a feature of the invention, the opening 74 of the hook 70 is just wide enough so that the bar plus the bottom 40 flange 56 of the slide 50 cannot be moved into said opening. The slide 50, however, has a notch 76, (Fig. 3) formed by cutting away the lower corner and part of the bottom face 56, which, when the slide is in 45 locking position, is in alinement with the hook 70. This serves to prevent the relative rotation of the roll and the collars 16 to locked position unless the slide 50 is also in position to lock the hooks 24 in place.

50 In the modified form of the invention illustrated in Figs. 7, 8 and 9, the actuator bar 32 is provided with overhanging hook portions 140 extending in the opposite direction from the hook portions 40 shown in 55 the device just described. The form of the paper-clamping hooks 24 is exactly like that of the hooks shown in connection with the other arrangement. In this arrangement, however, the locking device 150 is provided 60 with upstanding flanges 146 which, by co-operating with the hook portions 140 on the actuator bar, prevent the displacement of the paper-clamping hooks 24 from their positions beneath said portions 140. Inturned 65 lips 152 having upstanding flanges 154 cor-

respond exactly to the parts 52 and 54 in the preferred form of the device and the lower edge of the locking device is bent beneath the actuator bar as previously described.

70 Since the shanks 30 of the hooks 24 have been described as extending radially of the body of the roll, and the inner ends 42 have been described as extending parallel to the axis of the roll, and the flattened terminal or 75 clamping portions 28 are, as illustrated, disposed circumferentially of the roll, when the hooks 24 are in operative position, it will be clear that in whatever position the hooks 24 may assume, the terminal portions 28 and 80 42 will extend substantially at right angles to the shank portion 30 and to the planes defined by each other and by the shank portion 30.

Having described my invention, what I 85 claim as new and desire to secure by Letters Patent of the United States is:—

1. A finishing tool comprising a cylindrical body, a cover wrapped around said cylindrical body, means for binding said cover 90 upon the body comprising hooks movable radially of the body to clamp the cover, and a common actuator for effecting said radial movement of said hooks, said hooks and said actuator being constructed and arranged for 95 relative movement to bring them into interlocking engagement, the direction of said relative movement being longitudinal with respect to the axis of said cylindrical body.

2. A finishing tool comprising a body 100 adapted to receive and support a cover, means for clamping said cover on the body comprising a clamping hook having an exposed end arranged to overhang and clamp the cover and a shank movable in and out of 105 said body, and a rigid actuator disposed within the body of the tool provided with a shoulder having an undercut recess, the inner end of said hook being constructed and arranged to enter said recess to effect interlocking engagement with said actuator.

3. A finishing tool comprising an elongated roll adapted to receive and support a cover, a rigid actuator bar extending longitudinally of and within said roll and adapted 115 for movement radially thereof, said actuator bar being provided with an undercut recess, and a hook for clamping said abrasive cover provided with an exposed portion for engagement with the cover, a shank portion extending into the body of the cylindrical roll, and a hook-shaped inner end adapted to be moved into the undercut recess of said actuator to interlock the two devices by reason of such engagement, and 120 means movable with respect to said actuator arranged to retain said hook in interlocking engagement with said rigid actuator.

4. A finishing tool for use in the manufacture of boots and shoes, comprising a body, 130

a resilient pad on said body adapted to receive and support a finishing cover, and means for clamping said cover upon said pad-covered body comprising an actuator bar provided with hook-shaped portions having overhanging shoulders disposed wholly within the body of the roll and clamping hooks adapted by movement lengthwise of the bar to be brought into holding position under the shoulders of the hook-shaped portions of said actuator bar within the body of the roll.

5. A finishing tool for use in the manufacture of boots and shoes, comprising a rotatable body adapted to receive and support a finishing cover, and means for clamping said cover upon said body comprising an actuator bar disposed inside the body and a plurality of clamping hooks adapted to be inserted radially into the body and movable independently axially of the body to bring said hooks successively into interlocking engagement with said actuator bar.

6. A finishing tool for use in the manufacture of boots and shoes, comprising a rotatable body adapted to receive and support a finishing cover, and means for clamping said cover upon said body comprising an actuator bar disposed inside the body, a plurality of clamping hooks adapted to be inserted radially into the body and movable independently axially of the body to bring said hooks successively into interlocking engagement with said actuator bar, and means 35 movable longitudinally of said actuator bar constructed and arranged to complete the engagement of the hooks with the bar and to hold them in locked relation.

7. A finishing tool for use in the manufacture of boots and shoes, comprising a rotatable body adapted to receive and support a finishing cover, means for clamping said cover upon said body comprising an actuator bar disposed inside the body, a plurality of clamping hooks adapted to be inserted into the body and constructed and arranged to be individually moved into locking engagement with the actuator bar, and a common locking means for holding said hooks in engagement with said bar.

8. A finishing tool for use in the manufacture of boots and shoes, comprising a rotatable body adapted to receive and support a finishing cover and provided with a radial recess, means for clamping said cover to said body comprising an actuator bar provided with an overhanging hook-shaped portion having its open side closely adjacent to one side of said recess and a clamping hook adapted to be brought into engagement with the finishing cover by radial movement of said actuator bar, said bar and clamping hook being so constructed and arranged that the clamping hook and the hook-shaped portion of the bar may be brought into inter-

locking engagement by relative movement between the bar and the hook in a direction parallel to the axis of the tool.

9. A finishing tool for use in the manufacture of boots and shoes, comprising a cylindrical roll adapted to receive and support a finishing cover, a resilient cover for said roll provided with a plurality of narrow slots elongated longitudinally of the roll, an actuator bar disposed beneath the slots of said resilient cover having a plurality of recessed projections, and means for clamping the finishing cover over said resilient cover comprising a plurality of hooks adapted to be inserted through the slots in said resilient cover and moved longitudinally of the roll into interlocking engagement with the recessed projections of the actuator bar.

10. A finishing tool for use in the manufacture of boots and shoes, comprising a cylindrical roll adapted to receive and support a finishing cover, a resilient cover for said roll provided with a plurality of narrow slots, an actuator bar disposed beneath the slots in said resilient cover having undercut 90 recesses opening longitudinally of the bar, and means for clamping the abrasive cover over said resilient cover comprising a plurality of hooks having their inner ends bent in a direction parallel to the length of said bar and adapted to be passed through the slots of the resilient cover and moved individually into locking engagement with the recesses of the actuator bar.

11. A finishing tool for use in the manufacture of boots and shoes, comprising a body adapted to receive and support a finishing cover, and means for clamping said cover on said body comprising an actuator bar and cover-clamping hooks disposed within the body, said bar and hooks being arranged for mutual interlocking engagement, said hooks being detachably engaged with said actuator bar, and additional means for holding said hooks in engagement with the actuator bar after they have been interlocked comprising a locking device movable lengthwise of the actuator bar and constructed of sheet metal folded around said bar.

12. In an abrading tool, a body adapted to receive and support an abrasive cover and means for clamping said cover on said body, comprising an actuator bar disposed within the body, cover-clamping hooks detachably interlocked with said actuator bar, and means for holding said hooks in hooked engagement with the actuator bar comprising a shifting abutment frictionally engaging said bar constructed and arranged in one position to abut the hooks and thereby to keep them from unhooking.

13. A buffing tool comprising a rotatable body adapted to receive and support an abrasive cover, and means for clamping said cover upon said body comprising an actu-

5 ator bar disposed within the body and having hook-shaped extensions opening laterally and longitudinally of the bar, cover-clamping members detachably interlocked with said extensions, and means for preventing accidental lateral disengagement of said clamping members and said bar upon relative movement thereof circumferentially of the tool.

10 14. A buffing tool comprising a rotatable body adapted to receive and support an abrasive cover, and means for clamping said cover upon said body comprising an actuator bar disposed within the body and having recessed lateral extensions, cover-clamping members detachably interlocked with said extensions, and means for preventing disengagement of said clamping members and said bar upon relative movement there-

15 20 of axially of the tool.

15 25 16. A buffing tool comprising a rotatable body adapted to receive and support an abrasive cover, and means for clamping said cover upon said body comprising an actuator bar disposed within the body and having recessed lateral extensions, cover-clamping members detachably interlocked with said extensions, and means movable longitudinally of the tool arranged in one position to prevent relative unhooking movement of the clamping members and the bar in a direction parallel to the axis of the tool.

30 35 40 45 17. A buffing tool comprising a rotatable body adapted to receive and support an abrasive cover, and means for clamping said cover upon said body comprising an actuator bar disposed within the body and having open hook-shaped extensions, cover-clamping members detachably interlocked with said extensions by interengagement therewith, and means comprising a plate folded around said bar and movable longitudinally of the roll arranged in one position to prevent disengagement and resultant unlocking of said clamping members from said hook-shaped extensions.

50 55 60 65 18. For an abrading roll, a cover-retaining hook comprising a shank portion extending substantially radially of said roll, and terminal portions extending substan-

tially at right angles to said shank portion and to the planes defined by each other and the shank portion.

19. An abrading tool comprising a rotatable body adapted to receive and support an abrasive cover, and a radially disposed cover-clamping member having a flattened outer terminal portion overlying one edge of the abrasive cover and a cylindrical shank portion bent into a hook shape at its inner 75 end.

20. An abrading tool comprising a rotatable body adapted to receive and support an abrasive cover, and a cover-clamping member having a flattened outer terminal portion overlying one edge of the abrasive cover and a cylindrical shank portion bent into a hook shape at its inner end, said inner end extending in a direction parallel to the axis of the tool.

21. A finishing tool for use in the manufacture of boots and shoes comprising a body adapted to receive and support a finishing cover, means for clamping said cover on said body comprising a radially movable actuator 90 bar disposed within the body cover, clamping hooks detachably engaged with said actuator bar, means for holding said hooks in engagement with the actuator bar comprising a locking device movable lengthwise 95 of the bar, and a hook disposed midway of the roll to receive and support the actuator bar in its inner position, said locking device being constructed and arranged to prevent engagement of the actuator bar with the 100 hook in one position of the locking device.

22. A finishing tool for use in the manufacture of boots and shoes comprising a body adapted to receive and support a finishing cover, end collars secured to the 105 driving shaft to position said body upon the shaft, means for clamping the cover upon the body comprising an actuator bar disposed for radial movement within the body as said body is rotated with respect to the 110 end collars, cover-clamping hooks detachably engaged with said actuator bar, means for holding the said hooks in engagement with the actuator bar comprising a locking device movable lengthwise of the actuator 115 bar, and a retaining hook secured to said end collars and disposed midway of the roll adapted to receive and support the actuator bar in its inner position, said locking device being constructed and arranged to prevent 120 engagement of the actuator bar with the hook unless the locking device is in position to retain the hooks in engagement with the bar.

23. A finishing tool comprising a cylindrical body, a cover wrapped around said cylindrical body, means for binding said cover upon the body comprising hooks movable radially of the body to clamp the cover, a common actuator for effecting said radial 130

- movement of said hooks, said hooks and said actuator being constructed and arranged for relative movement to bring them into interlocking engagement, the direction 5 of said relative movement being longitudinal with respect to the axis of said cylindrical body, and means for holding said hooks and said actuator in interlocked relation.
- 10 24. A finishing tool comprising a roll adapted to receive and support a cover, means for clamping said cover on the roll comprising a hook having an exposed end arranged to overhang and clamp the cover 15 and a shank movable in and out of said roll, and an actuator disposed within the body of the roll for effecting said in and out movement of the shank of said hook, said hook and said actuator being constructed and arranged to provide for engagement of said hook with said actuator by 20 a translatory movement of said hook par-

allel to the axis of said roll, said roll having a slot for the shank of said hook, said slot being elongated in a direction parallel to the axis of said roll to accommodate said translatory movement of said hook. 25

25. A buffing tool comprising a rotatable body adapted to receive and support an abrasive cover, and means for clamping said cover upon said body comprising an actuator bar disposed within the body and having hook-shaped extensions opening laterally and longitudinally of the bar, and cover-clamping members detachably interlocked with said extensions, said rotatable body being constructed and arranged to prevent accidental lateral disengagement of said clamping members and said bar upon relative movement thereof circumferentially of the tool. 30 35

In testimony whereof I have signed my name to this specification.

ERNEST ASHTON.
